(57) **CLAIM**

The ornamental design for vehicle furniture, as shown and described.

DESCRIPTION

FIG. 1 is a perspective view of vehicle furniture showing my new design with a table down and a bed down;

FIG. 2 is a top plan view thereof;

FIG. 3 is a front elevational view thereof;

FIG. 4 is a rear elevational view thereof;

FIG. 5 is a right side elevational view thereof;

FIG. 6 is a left side elevational view thereof;

FIG. 7 is a perspective view of the vehicle furniture showing the table up and the bed up;

FIG. 8 is a top plan view thereof;

FIG. 9 is a front elevational view thereof;

FIG. 10 is a rear elevational view thereof;

FIG. 11 is a right side elevational view thereof;

FIG. 12 is a left side elevational view thereof;

FIG. 13 is a perspective view of vehicle furniture showing the table down and the bed up;

FIG. 14 is a top plan view thereof;

FIG. 15 is a front elevational view thereof;

FIG. 16 is a rear elevational view thereof;

FIG. 17 is a right side elevational view thereof; and,

FIG. 18 is a left side elevational view thereof.

The broken lines showing the environment are for the purpose of illustration and form no part of the claimed design.
